United States Patent

Des. 236,482
Patented Aug. 26, 1975

236,482

CONSOLE FOR A DATA SYSTEM

Richard G. Clayton, Detroit, and Jerry J. Sims, Southfield,
Mich., assignors to Burroughs Corporation, Detroit,
Mich.

Filed Aug. 27, 1973, Ser. No. 391,787

Term of patent 14 years

Int. Cl. D14—02

U.S. Cl. D26—5 C

The single figure is a front perspective view of a console for a data system showing our new design. The left side of the unit which is not shown is flat and the rear of the article which is not shown is substantially unornamented.

We claim:

The ornamental design for a console for a data system, substantially as shown and described.
